PARAFFIN BAG

Stanley R. Howard, Milton, Mass., assignor to
Pneumatic Scale Corporation, Limited, Quincy,
Mass., a corporation of Massachusetts

Application August 3, 1934, Serial No. 738,257

5 Claims. (Cl. 229—53)

This invention relates to a paraffin bag, and more particularly to a paraffin liner for a carton.

The invention has for an object to provide a novel construction of bag possessing superior moisture-resisting properties, which may be 5 economically manufactured and is particularly adapted for use as a paraffin liner for a carton.

With this general object in view and such others as may hereinafter appear, the invention consists 10 in the paraffin bag and in the paraffin liner for a carton hereinafter described and particularly defined in the claims at the end of this specification.

In the drawing illustrating the invention as 15 embodied in a paraffin liner for a carton, Fig. 1 is a perspective with portions broken away, illustrating the liner with the carton; Fig. 2 is a similar view illustrating the liner ready for introduction into the carton; Fig. 3 is a plan of a paraffin coated paper web from which the present 20 liner may be produced; Fig. 4 is a view in side elevation illustrating the liner in its partially completed condition; Fig. 5 is a plan view of the liner in the condition shown in Fig. 4; and Fig. 6 is an end elevation of the lower portion of the 25 liner shown in Fig. 4.

Prior to the present invention, many attempts have been made to produce a satisfactory paraffin liner for a carton, but the results of all of these 30 attempts have for one reason or another been commercially unsatisfactory. The general commercial practice has been to produce the paraffin liner from a web of paraffin paper by folding the web to form a bag rectangular in section and 35 with overlapping side seams and then to apply heat to the side seams to fuse the paraffin to cause the overlapping portions to adhere together. The effect of the heat when applied to the overlapping side seams has been to melt the paraffin 40 and cause it to run from the overlapping strip leaving an overlapping side seam at each side of the liner which is deficient in paraffin, and in most instances the resulting side seams are converted into substantially uncoated strips possessing 45 little or no moisture resistance and destroying most of the effectiveness of the paraffin liner as a moisture-resisting agency. The packaging of certain types of hygroscopic material has presented very serious packaging problems, and the 50 use of paraffin liners has been resorted to in the attempt to provide a satisfactory moisture-resisting liner and package, in order to prevent access of the moisture-laden air into the interior of the package. When the continuity of the 55 coating of paraffin is substantially destroyed by

the application of heat to the side seam, even though enough paraffin remains upon the side seam to effect the adherence of the overlapping portions of the seam, nevertheless through this deficient strip the moisture-laden air can readily 5 pass, destroying the effect which is sought to be produced by the use of the paraffin liner.

Other attempts to solve the problem have included the use of special adhesives, but these materials have all included solvents whose 10 pungent odors have rendered their use prohibitive for the packaging of food products.

In accordance with the present invention the improved bag is produced of a unitary length 10 of paper provided upon both surfaces thereof 15 with coatings 12 of paraffin or equivalent waterproofing material of a substantial thickness sufficient to effectively resist the passage of moisture through. The paraffin coating upon that surface of the sheet which is to constitute 20 the inner surface of the liner or bag is arranged to terminate at a line 14 spaced from each marginal edge 15 of the sheet a distance corresponding to the desired width of side seam to be produced in the bag when formed. This produces at 25 each marginal edge of one surface of the sheet a strip which is free or substantially free from paraffin.

In producing the present bag, the unitary length 10 of the paraffin-coated paper is then 30 folded preferably to form a rectangular shaped bag, and the folds are made so as to bring into contact the two substantially paraffin-free strips or surfaces, and the latter are adhesively affixed to each other by glue or other adhesive, producing a 35 strong and durable side seam. In addition, the formation of the bag is arranged so that the coating 12 of paraffin upon the inner surface of each half of the bag is brought into abutment or contact as at 20, 21, so that as a result of this 40 construction the ultimate bag is provided with an interior coating of paraffin which extends entirely around the entire inner surface thereof and forms a complete moisture-resisting barrier of substantial thickness, rendering the paraffin bag thus 45 produced highly efficient as a moisture-resisting container, and particularly as a moisture-resisting liner for a carton or package.

After the side seams have been adhesively 50 affixed together by glue, producing an exceptionally strong paper to paper contact and seam, the side seams may and preferably will be folded into contact with the end surfaces of the bag in the manner illustrated in Fig. 1, and the projecting lower portion of the sides of the bag folded 55

up into the position shown in Figs. 1 and 2, and as a result the complete paraffin liner thus formed is ready to be inserted into the package.

The present construction of bag, involving the formation thereof from a single unitary length of coated paraffin web, produces a most satisfactory moisture-resisting bottom of the bag. Heretofore, considerable difficulty has been experienced in producing a satisfactory moisture-resisting bottom in bag-forming machines, and as a result of the present construction of bag, a one-piece bottom with no seams therein is produced, and in which both sides of the paper web forming the bottom are coated with a substantial coating of paraffin.

As used throughout the specification and claims, the term "paraffin" is intended to include those various commercial moisture-resisting coatings which present difficulty in the use of an adhesive in the production of side seams.

While the preferred form of the invention has been herein illustrated and described, it will be understood that the invention may be embodied in other forms within the scope of the following claims.

Having thus described the invention, what is claimed is:—

1. A moisture-resisting bag comprising a body portion formed of a unitary length of paper coated on both sides with a layer of paraffin of substantial thickness and having the marginal portions of the surface which is to form the interior of the bag substantially free from paraffin, said paper length being folded in such a manner as to permit the paraffin-free surfaces to be brought into contact and adhesively secured together to form outwardly projecting side seams and in such a manner that the paraffin layer on the interior of one half section of the bag will meet with the corresponding paraffin layer of the other section, whereby the bag is provided with a wall of paraffin of substantial thickness over the entire inner surface thereof.

2. A moisture-resisting bag comprising a body portion including side portions and formed of a unitary length of paper coated on both sides with a layer of paraffin of substantial thickness and

having the marginal portions of the surface which is to form the interior of the bag substantially free from paraffin, said paper length being folded in such a manner as to permit the paraffin-free surfaces to be brought into contact and adhesively secured together to form outwardly projecting side seams and in such a manner that the paraffin layer on the interior of one half section of the bag will meet with the corresponding paraffin layer of the other section, whereby the bag is provided with a wall of paraffin of substantial thickness over the entire inner surface thereof, said outwardly projecting side seams being folded against the side portions of the bag.

3. A paraffin coated bag composed of a single paraffin-coated paper sheet folded to form the body of the bag and to form outwardly projecting side seams extending lengthwise of the bag, the contacting faces of the paper forming said side seams being paraffin-free and tightly glued together whereby to provide the entire interior of the body portion of the bag with a uniform and moisture-resisting paraffin coating.

4. A moisture resisting bag of the seamless bottom type comprising a paraffin coated paper sheet having its side edges folded to form side portions with outwardly projecting margins extending lengthwise of the bag, said margins having their contacting faces substantially paraffin-free and adhesively and tightly affixed to one another to form side seams with the paraffin layer on the interior of one half section of the bag meeting with the corresponding paraffin layer on the other half-section of the bag, said side seams being folded against opposed side portions of the bag.

5. A moisture-resisting bag comprising a paraffin-coated sheet folded to form the body of the bag with outwardly projecting side seams extending lengthwise of the bag, the contacting faces of the paper forming said side seams being substantially paraffin-free and adhesively and tightly affixed to one another whereby to form a bag possessing a high degree of moisture resistance.

STANLEY R. HOWARD.
